UNITED STATES PATENT OFFICE.

NATHANIEL O. GOLDSMITH, OF NORWOOD, OHIO, ASSIGNOR TO THE WEIR FROG COMPANY, OF NORWOOD, OHIO, A CORPORATION OF OHIO.

SWITCH-STAND.

1,165,244.

Specification of Letters Patent. Patented Dec. 21, 1915.

Application filed July 6, 1915. Serial No. 38,066.

To all whom it may concern:

Be it known that I, NATHANIEL O. GOLDSMITH, a citizen of the United States, and a resident of the city of Norwood, in the county of Hamilton and State of Ohio, have invented certain new and useful Improvements in Switch-Stands, of which the following is a full, clear, and exact description, reference being had to the accompanying drawings, forming part of this specification.

My invention relates to switch stands of the adjustable type wherein play is allowed for the connecting rod and its operative connection with the throw crank.

It has as its object the providing of certain structural improvements which simplify the manufacturing cost and protect the various connections in the stand from chance dislodgment and from becoming clogged by mud or ice, and has further as its object the providing of a lost motion mechanism which is located between the switch rail head rod and the stand. These objects I accomplish by that certain construction and arrangement of parts to be hereinafter more specifically pointed out and claimed and the various advantages noted.

In the drawings, Figure 1 is a rear elevation of the stand. Fig. 2 is an elevation of the connecting rod on a larger scale, partly broken away to show the structure of the adjustable nut and sleeve. Fig. 3 is a top plan view of the stand connected up to a switch. Fig. 4 is a sectional view through the cotter pin of one of the slotted adjustable nuts. Fig. 5 is a vertical sectional view taken through the pin that connects the rod and the crank of the stand, said pin being shown in elevation. Fig. 6 is a longitudinal sectional view of a modified form of lost motion device for the connecting rod. Fig. 7 is an elevation of the same. Fig. 8 is a detail end elevation of the sleeve coupled to a switch stand crank in a modified manner. Fig. 9 is a side elevation of a further modified form of lost motion device. Fig. 10 is a detail elevation of a further modified form of sleeve and crank. Fig. 11 is a longitudinal section of the part shown in Fig. 9.

Whereas but one type of switch stand is shown and described, it will be understood

that the various modified types of lost motion device are applicable to stands of different types. It is to be further noted that the various modifications, although differently constructed, all have alike the common characteristic of being protected from ice and sediment, and capable of being connected pivotally to the switch rail head rod, thus being capable of application with equal advantage to any form of switch.

I will first describe the principal form of lost motion device exemplifying my invention, together with the type of stand and the preferred method of coupling the stand to the connecting rod to which the said lost motion device is to be applied. After the description of these parts, I will then describe the various modifications of lost motion device which have a wider application.

The connecting rod 1 of the device has a fork 2 for coupling it with the switch rail head rod 3 that throws the movable rails 4, 5, of any desired switch. The stand has a base 6, in which is mounted the transverse shaft 7 that is preferably integral with the switch lever 8. Journaled in the upper part 80 of the stand is the vertical shaft 9 of the target 10. This target shaft extends out through the bottom of the stand and formed integral with it is the crank 11, which imparts motion to the connecting rod 1. For 85 operating the vertical shaft, beveled pinions, 12 for the transverse shaft, and 13 for the vertical shaft are provided, said pinions being forged integral with their shafts.

The connecting rod sleeve has a U-shaped 90 base 14 to fit over the flattened end 15 of the crank 11. The body portion 16 of the sleeve extends in both directions from the U-shaped base, and slidingly engages over the screw-threaded end 17 of the connecting rod 1. 95 The top central portion of the sleeve portion is cut away leaving an aperture directly over the U-shaped base portion, which said aperture is covered by an arched cover plate 18 that is adapted to be screwed down over 100 the aperture. There is provided through the U-shaped base portion above and below an aperture for the securing pin 19, and the crank end 15 is also formed with a suitable hole for such pin. The pin has a head 20 105 which seats in the base of the sleeve, which is countersunk around the pin aperture so that the head will lie flush with the sleeve

and not interfere with its sliding on the connecting rod.

In mounting the sleeve, the U-shaped portion is placed over the end of the crank. 5 The pin is then dropped into place and the connecting rod slid into the sleeve. The rod will then be in a position to hold the pin in place and the cover plate 18 is screwed down over the aperture at the upper side 10 of the sleeve to keep out the weather. A cotter pin may be inserted in the hole 21 in the protruding end of the pin.

The two adjustable nuts are of a special construction to provide for play in the 15 movement of the connecting rod, to be securely held against backing off, thus destroying all adjustments, and to keep mud and ice out of the space left for lost motion, so that this will not be stopped off. The 20 nuts accordingly have a screwthreaded body portion 22 which screws onto the end of the connecting rod, and a sleeve portion 23 which fits over the ends of the sleeve portion 16 above mentioned. The nuts are provided with inclosed slots 25, preferably four 25 in number, to allow for quarter turns of the nuts, and the end of the connecting rod is slotted so that cotter pins 26 may be used to hold the nuts in any desired position. The 30 nuts are to be positioned with relation to the sleeve so that the sleeve may slide the desired distance before striking the body portion of the nuts. The nuts are mounted, one on one side and one on the other side of 35 the sleeve, and the sleeve portions of the nuts are to be made long enough to fully cover over the ends of the main sleeve in all positions.

The modification shown in Figs. 6 and 7 40 comprises the rod 1 having the forked end 2 for connection with the switch rail head rod, and the screwthreaded end 17. The sleeve 30 in this instance, however, does not carry a depending U-shaped portion, but on the 45 contrary extends horizontally over the end of the rod, the outer end of the sleeve being expanded at 31 to form a hood to engage over the adjustable nut 32 on the end of the rod. The sleeve then separates into two 50 arms 33, 33, which can be coupled up to a switch stand crank, or if desired could be connected up with any desired member actuated by the said crank. The other adjustable abutment nut is like the sleeved nut 55 already described and has the screwthreaded body portion 22 and the sleeve 23 to engage over the inner end of the sleeve. It can be seen that this modification has the same advantages in supplying a lost motion device 60 of simplicity, economy and security, and is in addition capable of being used with any form of switch and switch stand by merely inserting it into the interconnecting members between the switch and stand.

65 As shown in Figs. 8 and 10, a sleeve 40 is

provided which may be of similar structure to the sleeve 16 formerly described, and it may be used with the two sleeved nuts 22 described in connection with said sleeve 16. However, the sleeves in this instance are 70 mounted differently on the switch stand crank end 15, the one in Fig. 8 having a U-shaped portion like the sleeve 16 but being connected to the crank by an upwardly extending bolt 41, which merely screws into 75 the sleeve, and the sleeve therefor not being necessarily open at the upper end for the insertion of the bolt. In the sleeve of Fig. 10, the means for securing it to the crank comprises two lugs 42, 42, which are provided with apertures for the bolt 43, which 80 couples the end of the crank to the lugs.

The modification shown in Figs. 9 and 11 85 has a sliding sleeve 50, provided with lugs 51 for receiving a coupling bolt. The sleeve 5 has both of its ends interiorly expanded at 52, to form hoods for slidably engaging over the nuts 53. These nuts are not shown as being slotted, but they may be slotted if desired. They have the enlarged ends 54 90 which form the abutments for the ends of the sleeve.

It can be seen that the modifications now briefly noted enable my invention to be used with varying types of switches now in use, 95 or specially constructed for meeting the requirements of peculiar situations.

It is believed that the various advantages resulting in the structure having been sufficiently mentioned during the progress of the 100 description, so as to require no further particular statement.

Having thus described my invention, what I claim as new and desire to secure by Letters Patent, is:—

1. In a switch stand, in combination with a connecting rod, a crank engaging at the base of said sleeve, a pin with its head seated in the interior of the sleeve, the crank member and its engaging member having 110 apertures to receive said pin, whereby the connecting rod in the sleeve will lock said pin in place.

2. In a switch stand, in combination with a connecting rod, and a crank member, a 115 sleeve for the connecting rod, a crank engaging member at the base of said sleeve, a pin with its head seated in the interior of the sleeve, the interior of the sleeve having a countersink for the pinhead, and the crank member and its engaging member having apertures to receive said pin, whereby the connecting rod in the sleeve will lock said pin in place.

3. In a switch stand, in combination with 125 a connecting rod, and a crank member, a sleeve for the connecting rod, a U-shaped crank engaging member at the base of said sleeve, a pin with its head seated in the interior of the sleeve, the crank member and 130

its engaging member having apertures to receive said pin, whereby the connecting rod in the sleeve will lock said pin in place.

4. In a switch stand, in combination with 5 a connecting rod, and a crank member, a sleeve for slidably engaging the connecting rod, pivotal connection therefor with the crank member comprising a U-shaped member on the sleeve, a flattened end on the 10 crank, and a pivot pin for said U-shaped member and flattened end.

5. In a switch stand, in combination with a connecting rod, and a crank member, a sleeve for slidably engaging the connecting 15 rod, pivotal connection therefor with the crank member comprising a U-shaped member on the sleeve, a flattened end on the crank, a pivot pin for said U-shaped member and flattened end, and means whereby 20 the inserting of the connecting rod into the sleeve will lock said pin in place.

6. In a switch stand, in combination with a connecting rod, and a crank member, a sleeve for slidably engaging the rod, connection 25 from the sleeve to the crank, and nuts on the connecting rod for forming abutments for the sleeve, and means for closing off the spaces between the nuts and the sleeve ends from the weather without 30 inclosing the nuts to prevent easy adjustment thereof.

7. In a switch stand, in combination with a connecting rod, a crank member, a sleeve for slidably engaging the rod, connection 35 from the sleeve to the crank, and nuts on the connecting rod for forming abutments for the sleeve, and means for closing off the spaces between the nuts and the sleeve ends from the weather, comprising sleeves open 40 at the ends extending across said spaces.

8. In a switch stand, in combination with a connecting rod, a crank member, a sleeve for slidably engaging the rod, connection from the sleeve to the crank, and nuts on the 45 connecting rod for forming abutments for the sleeve, and means for closing off the spaces between the nuts and the sleeve ends from the weather, comprising sleeves extending across said spaces, said sleeves located on the nuts and engaging over the outside of the connecting rod sleeve.

9. In a switch stand, in combination with a connecting rod, and a crank member, a sleeve for the connecting rod, and a pivot

pin for connecting said sleeve and crank, 55 said pin located with its head in the base of the sleeve, for the purpose described.

10. In a switch stand, in combination with a connecting rod, and a crank member, a sleeve for the connecting rod, and a pivot 60 pin for connecting said sleeve and crank, said pin located with its head in the base of the sleeve, said sleeve having an aperture in its upper side for inserting said pin in assembling the parts, for the purpose de- 65 scribed.

11. In a switch stand, the combination of a crank with a sliding member coupled thereto, and a rod having abutments which alternately engage such sliding member and 70 means for protecting the space between the sliding member and the abutments without concealing said abutments.

12. In a switch stand with a crank member, the combination of a rod, a sleeve slid- 75 ingly engaging the rod, connection from the sleeve to crank and independently adjustable abutments on the rod and means for protecting the space between the sliding member and the abutments without concealing said abutments. 80

13. In a switch stand with a crank member, the combination of a rod, a sleeve slid- 85 ingly engaging the rod, connection from the sleeve to the crank, and independently adjustable abutments on the rod and means to lock separately each abutment to the rod and means for protecting the space between the sliding member and the abutments without concealing said abutments. 90

14. In a switch stand, the combination of a crank member hinged to a slideable sleeve engaging a rod, two adjustable abutments on the rod alternately abutting said sleeve, and means for locking said adjustable abut- 95 ments in a series of graduated positions to said rod comprising inclosed slots in the adjustable abutments and cotter pins therefor.

15. In a switch stand, the combination of 100 a rod, and slideable sleeve therefor, a crank member hinged to the slideable sleeve engaging a rod, two adjustable abutments on the rod, alternately abutting said sleeve, said adjustable members having slots and pins 105 engaging said slots for locking said members to the rod.

NATHANIEL O. GOLDSMITH.
